HOUSING FOR ENGINE

Rustan Lange, Jonkoping, Sweden, assignor to Kendale Industries, Inc., Independence, Ohio

Filed Aug. 27, 1969, Ser. No. 18,884

Term of patent 14 years

Int. Cl. D15—01

U.S. Cl. D77—1

Fig. 1

Fig. 3

Fig. 2

Fig. 4

Fig. 5

FIG. 1 is a perspective view of a housing for engine embodying my design;

FIG. 2 is a side view of the same, the opposite side being similar;

FIG. 3 is a front end view of the same;

FIG. 4 is a top plan view of the same, the bottom being plain; and

FIG. 5 is a rear end view of the same.

I claim:

The ornamental design for a housing for engine, substantially as shown and described.
